(57) **CLAIM**

The ornamental design for a locking hitch pin, as shown and described.

DESCRIPTION

FIG. 1 is a perspective view of the locking hitch pin.

FIG. 2 is a front elevational view of the locking hitch pin.

FIG. 3 is a rear elevational view thereof.

FIG. 4 is a top plan view thereof.

FIG. 5 is a bottom plan view thereof.

FIG. 6 is left side elevational view thereof.

FIG. 7 is a right side elevational view thereof; and,

FIG. 8 is a second perspective view of the locking hitch pin shown in an open position.

The broken lines showing in FIG. 8 are included for the purpose of showing unclaimed subject matter and form no part of the claimed design.

1 Claim, 5 Drawing Sheets
